UNITED STATES PATENT OFFICE.

JAMES A. DAWLEY, OF DENVER, COLORADO.

DESIGN FOR A WATCH-CHARM.

SPECIFICATION forming part of Design No. 21,718, dated July 19, 1892.

Application filed September 19, 1891. Serial No. 406,264. Term of patent 3½ years.

To all whom it may concern:

Be it known that I, JAMES A. DAWLEY, a citizen of the United States, residing at Denver, in the county of Arapahoe and State of Colorado, have invented and produced a new and original Design for Watch-Charms or Similar Articles, of which the following is a specification, reference being had to the accompanying drawing, forming a part there-
of.

The figure is a front view of a watch-charm, showing my design.

The leading feature of my design consists

in the several elements which comprise the figure of a dove 1, bearing in its mouth a palm-branch, a palm-branch 2 by itself, a log 3, of wood, with an ax 4 and a wedge 5 driven into it, and a beetle 6 lying beside the same, the whole being surrounded by the nine stars 7.

What I claim is—

The design for a watch-charm or similar article, as herein shown and described.

JAMES A. DAWLEY.
